ATTORNEYS:

UNITED STATES PATENT OFFICE.

HEINRICH HOROWITZ, OF NEW YORK, N. Y.

CULINARY GRATER.

SPECIFICATION forming part of Letters Patent No. 331,709, dated December 1, 1885.

Application filed May 7, 1885. Serial No. 164,672. (No model.)

To all whom it may concern:

Be it known that I, HEINRICH HOROWITZ, a citizen of the United States, residing at New York, in the county and State of New York, 5 have invented new and useful Improvements in Culinary Graters, of which the following is a specification.

My invention relates to improvements in graters, such as are used in culinary operations for the various purposes to which such devices are adapted; and it consists in the construction and combination of devices hereinafter described and claimed, reference being made to the accompanying drawings, illustrating my invention, in which—

Figure 1 is a face view, part in section, of my improved grater. Fig. 2 is a transverse section of the same in the plane $x x$, Fig. 1.

Similar letters indicate corresponding parts. 20 In the drawings, the letter A designates the grater, made of sheet metal or other suitable material, and having its longitudinal edges $a a$ rolled up for the reception of the arms $b b$ of a bent-wire frame, B, which arms snugly fit the roll, but are not securely clamped, so that the frame can be easily withdrawn or inserted therein when so desired. To retain the frame in position, the ends of the arms $b b$ of the frame are provided with screw-threads, 25 which are engaged by internal threads in nuts or buttons C, screwed on the said ends of the arms, said nuts or buttons also performing the functions of legs.

In the example shown in the drawings a 30 grater is illustrated which has a convex grating-surface; but the frame can be used just as expeditiously with a flat grater. However, when the frame is applied to such a convex grater I connect the arms $b b$ of the frame by 35 means of bars D D', preferably one at or near each end of the grater, which are removably secured to the said arms. One method of securing the same, as shown in the drawings, is to form an eye on each of the ends of the bars, 40 which eyes receive the arms of the frame, and the upper bar is retained in position by resting against the grater and a bend formed in the frame at that point, while the lower bar is held between the grater and the nuts or 45 buttons; but, if desired, the upper bar can be rigidly secured. The bars are intended to strengthen the grater, by resisting any force tending to "spread" the same, and are therefore of more service when a convex grater is

used; but they are also applicable to good 55 purpose in flat graters. The upper part of the frame is bent to form an ordinary wire handle; but for convenience in handling the grater I attach an ordinary wooden handle, e, thereto, which is put on during the process of 60 manufacture of the frame.

From the above description it will be readily perceived that the frame can be easily withdrawn from the grater by removing the nuts or buttons C and the lower stiffening-bar, 65 and it can be applied to a new grater when the old one is worn out or accidentally destroyed, while at the same time it renders the grater more convenient for use than without such a frame.

I am aware that the edges of graters have been turned over to receive a wire frame curved at the top to form a handle; but such frames are firmly secured to the grater, and are not therefore removable, as in the example shown and described.

What I claim as new, and desire to secure by Letters Patent, is—

1. The combination, with a culinary grater having tubular edges, of a detachable wire frame provided with two arms that are passed through said tubular edges, and detachable fastenings, that are also adapted to serve as legs for the grater, substantially as described.

2. The combination, with a convex grater, 85 A, having tubular edges, of the cross-bars D D', the wire frame comprising two arms extending through the tubular edges and engaging the bars, and screw-nuts or buttons fitting the extremities of the arms, substantially as 90 described.

3. As a new article of manufacture, a grater having tubular edges provided at each end with a cross-bar having eyes in their ends, a wire frame provided with a handle, and comprising two arms extending through the eyes of the bars and the tubular edges of the grater, and screw-nuts or buttons engaging the extremities of the arms, substantially as 95 described.

In testimony whereof I have hereunto set my hand and seal in the presence of two subscribing witnesses.

HEINRICH HOROWITZ. [L. S.]
